UNITED STATES PATENT OFFICE.

ROBERT HENDERSON DUNCAN, OF EPPING, NEAR SYDNEY, NEW SOUTH WALES,
AUSTRALIA.

SECURITY BOX OR CASE.

1,394,981.

Specification of Letters Patent.

Patented Oct. 25, 1921.

Application filed January 29, 1919. Serial No. 273,848.

To all whom it may concern:

Be it known that I, ROBERT HENDERSON DUNCAN, a citizen of the Commonwealth of Australia, residing at Epping, near Sydney, in the State of New South Wales, Commonwealth of Australia, have invented certain new and useful Improvements in a Security Box or Case, of which the following is a specification.

10 This invention relates to improvements in boxes or cases used for the transportation of goods of various kinds such as, eggs, fruit, food-stuffs, merchandise, and the like, and articles which it is desired should be delivered at their destination in their originally packed condition, unaffected by the tampering efforts of would-be purloiners and if in the event of such improper interference with the goods being made while 15 the boxes are in transit, it will be possible for the consignee (before accepting delivery) to ascertain that the case has been tampered with *en route*.

The improvements include means for safe- 25 guarding the united parts comprising the box or case, by suitably using and fixedly locating banding wire and cleats in positions which will prevent the easy detachment of the boards, either by instrumental 30 force, or by the rough usage common to the transportation of goods, and the handling of same carelessly. Further, provision is made to secure the detachable lid part in its rightful position by means of both in- 35 ternally and externally arranged attach- ments, combined with dual fastenings, with which is associated a locking device adapted to be in engagement with an address plate, a retaining spring, and a secretly confined 40 cord attachment, having its end, or ends, disposed in a safeguarding sinkage adapted to be sealed, and so covering the said ends of the cord, thus necessitating the severance of the attachment when the box reaches the 45 consignee.

The invention is illustrated by the accompanying drawings, in which similar letters of reference are used to indicate the same parts when shown in different figures, and 50 in which:—

Figure 1— is a perspective view of the box lid as seen on its underside, showing attachment parts and catch fastenings with associated plate.

55 Fig. 2— is a perspective view of the box

lid as seen on the outside, showing locking lever securing address plate also battens with security clips.

Fig. 3— is an angular perspective view of the box with lid thereon, showing sinkage 60 for receiving cord ends to be sealed, also banding wire in position.

Fig. 4— is an angular perspective view, taken in the opposite direction to Fig. 3, to show locking lever, address plate, and band- 65 ing wire.

Fig. 5— is a plan of the box without the lid, showing the companion fastenings for securing the lid, the internal attachments, secret cord and sinkage, also banding wire 70 continued into angle formations.

Fig. 6— is a plan of the box with lid in position, attached to rope loops, showing also batten clips, locking lever, address plate, and spring.

75 Fig. 7— is a plan (enlarged detail) showing a fragment of the lid with the locking lever and associated parts in their locked and safeguarded position.

Fig. 8— is a perspective (enlarged detail) 80 view of the internal dual fastenings, shown attached to fragments of the box and lid.

Fig. 9— is a perspective detail of the plate attachment for underside of lid, as seen in Fig. 8.

85 Fig. 10— is a perspective (enlarged detail) view of a lid attachment part and its associate part (dotted) shown attached to fragments of the box and lid.

Fig. 11— is a plan of internal fastenings 90 for lid in the disengaged position, also plate shown in Figs. 8 and 9.

Fig. 12— is an elevation (with woodwork in section) showing the fastenings in their engaged and locked position.

95 Fig. 13— is a further detail showing fastenings in Fig. 12 in the disengaged and unlocked positions, but with lever and attachments omitted.

Fig. 14— is a plan of sliding piece in its 100 engaged position.

The form of box or case shown in the drawings is of the kind suitable for the transportation of eggs, but the invention is equally serviceable to other known classes 105 of boxes with removable lids, or with lids loosely attached as shown in the drawings. Where the boxes are composed of boards having air spaces as for fruit transportation, the lids may be secured as in this in- 110

vention, and the wire banding and cleats similarly utilized.

In Figs. 3, 4 and 5, the box ends A, are overlapped by the side-pieces A¹, and the bottom portion A², which renders unnecessary the use of banding wire B, such as is inserted in the grooves A³, (saw-cuts) formed in the sides and bottoms. Security clips B¹, clenched within the box, prevent displacement of the wire (shown dotted in the side grooves) which is continued over the top edges and secured with clips to form angle pieces B², thus preventing forcible detachment, of the united wood parts.

In egg boxes the transverse end pieces A⁴, are used for lifting purposes, but I provide in them the hand grip formations A⁵, Figs. 8, 12, 13 to prevent slipping taking place as the boxes are handled.

In Figs. 5 and 10, an end piece is utilized to secrete and to further secure the angle pieces C, attached to an end box part. These are set at any suitable distance apart so as to slidably engage with their grooved companion plates C¹, fastened to the underside face of the lid D. The said plates when fully seated prevent endwise movement of the lid, *vide* Fig. 10, and also prevents its uplift at that end.

In the construction of egg boxes having lids of the "flush top" type, transverse stiffening pieces are attached to the underside of the lid, thus necessitating the lowering of the end pieces such as A⁴, to provide an upstanding margin or space which they occupy when the lid is in its position, but I find it desirable to avoid this form of construction by having a "flush" under-surface lid with its transverse pieces D¹, secured with angularly disposed corner clips D², passing through both woods and clenched underneath.

Intermediate nail fastenings serve to complete the construction. Besides being able to handle the lid more conveniently they serve to guard the fastening and secreting appliances by which the lid is rendered immovable and the contents of the box safeguarded. The fastening attachments are essentially combined both with the lid and the box, and although the drawings show only a single set of such when associated with an egg box, it is obvious that when applied to boxes or cases of large dimensions it would be desirable to use a suitable number according to requirements.

The lid attachment details appear in Figs. 7 to 13 inclusive, and the box attachment details in Figs. 8, 10, 12 to 14. The several parts of the lid attachments, are the before-mentioned angle pieces C, with their grooved companion plates C¹, by which the lid is held in position at one end. At the other end security of fastening is obtained by means of a stem piece or spindle E, passing

downwardly through the washer E¹, and the lid D. Outside the lid, the locking lever F, secured to the spindle, is made serviceable by its gapped formation F¹, to engage with the upstanding part H, of the laterally sliding bolt H¹, which forms part of the box attachment. The aforesaid spindle is held in position by the angle plate G secured to the underside of the lid, the downwardly extending length being squared to hold the barrel formation E², with its extending catch E³, the parts being further secured by the screw threaded nut E⁴, attached to the threaded spindle end. The aforesaid angle plate G, is provided with the hook shaped part G¹, which serves the dual purpose of a centralizer and sliding bolt holder when lowered into the gapped formation H², provided between barrel parts H³ and H⁴, which are homogeneous with the plate H⁵ secured to the box part A, as in Figs. 12 to 14, by the screws H⁶. The plate H⁵, is further provided with the angle piece H⁷, with its gap H⁸, in which is to be located the barrel part E², to serve as a centralizer in association with the before mentioned hook shaped part G¹, as in Fig. 11, which shows the catch E³, in its disengaged position to allow of the barrel shaped part entering the gap H⁸, as is also indicated in Fig. 14, in dotted lines. This is the essentially normal position of the catch part E³, before the lid is placed in its right position for locking by the rotation of the lever F, which has the effect of placing the said catch beneath plate H⁷, as shown in Fig. 8.

In Fig. 12, the box attachments are shown in combination with the lid attachments, all in their secured and locked positions, but in Fig. 13, the spindle E, and the parts belonging thereto are wholly omitted to show more clearly the centralizing part G¹, of the angle piece G, fitting into the gap H², as it would appear when the lid is lowered before the bolting and locking action can take place. The bolt H¹ is there shown withdrawn, in which case the lever F, would be in the position as indicated by the dotted lines in Fig. 7. To allow the bolt stem H, to be operated from above the lid D, the channel I, is provided in the lid, and the cutaway I¹, in the batten D¹. The horizontal groove J, is used to partly secrete the lever F, and the end part of the address plate, K with which it is associated as in Fig. 7, the engagement being made at the hook part K¹. The said plate at its outer end is placed under the bridging piece L, and held by the curved overlapping part K², to facilitate its withdrawal and after lever F is rotated the tag part K³ is used. The bridge piece L, stands at a sufficient height above the lid surface to allow the address plate to pass, the turned down ends piercing the lid and are secured by clenching underneath. The

spring M, serves to hold the lever in its locked position, by being placed in engagement with the turned-up end F², of the lever, the security cord N, being passed around 5 same, and thence through the secreting channel O, and down the channel P, into the sealing receptacle Q, when it may be covered with sealing wax on which may be impressed the consignor's initials or monogram or trade 10 mark, as may be considered desirable. As before stated the lids may be either wholly removable or they may be loosely attached to the boxes by means of looped attachments D³, inserted in holes provided in suitable 15 positions.

The address plate K as shown in Fig. 7 consists of a metal plate K, having an engagement hook K¹, to receive the lever F when rotated into the engagement and locking 20 position shown in Fig. 7. The said plate is passed under the bridge-piece L which serves as a guide and which is secured to the lid D. The curved end K² is shown in engagement with the said bridge-piece. The 25 tag part K³ is provided to facilitate the withdrawal of the plate after the lever F has been released from engagement with the spring M, and the cord attachment N, confined in the channel O and sealed in the 30 receptacle Q formed in the side of the case.

Having now described my invention, what I consider novel and desire to secure by Letters Patent is:—

1. In a guarantee case or box, case and 35 lid attachment interlocking parts, coincidentally arranged on the separable parts thereof; the lid part having transverse end pieces, angularly disposed corner clips clenched on the under surface of the lid for 40 securing the end pieces, one such end piece—located adjacently to the lid locking attachment—having a cord secreting channel thereunder and which is continued downwardly to the sealing formation, a bolt, the 45 lid having a channel for bolt stem to slide in, the end piece being cut away for said stem, a spindle, a gapped lever attached outwardly to the spindle, the spindle located downwardly in the lid, a hook shaped centralizing plate secured to underside of lid, 50 a combined barrel and catch attached to spindle and operated by the said lever,

grooved companion plates attached to underside of lid, and securing angle plates attached to the box parts contiguous thereto, 55 and engaged by the companion plates.

2. In a guarantee case or box having both the case and lid attachment interlocking parts, coincidentally arranged on the separable parts thereof; the combination comprising the interiorly located bolt casing having a tubular portion and having a gapped formation, a centralizing hook shaped plate received and secured in the gapped formation of the casing and attached to the case lid, a gapped angle plate located below said gap and forming an integral part of said casing, a slidable bolt moving in the tubular portion of casing and having an upstanding stem adapted to be 70 operated from outside the box, the said bolt slidably engaging with the aforesaid centralizing plate, an exteriorly located operating lever gapped to engage with the upstanding stem of the slidable bolt, and 75 further having a turned up end part to form cord attachment, and a spindle on said lever having on its downward end a combined tubular and catch formation in engagement with the lowermost gapped plate which is 80 part of bolt casing.

3. In a guarantee case or box having both the case and lid attachment interlocking parts, coincidentally arranged on the separable parts thereof: the combination 85 comprising the parts claimed in claim 2, with an address plate having a central withdrawing hook formation, a bent end part to be in engagement with a lid bridge, a 90 forwardly located hook formation to be engaged by the locking lever, a recoil spring to retain said locking lever in its engaged position, an engaged cord attached to such lever, and thereafter secretly located in the 95 channeled parts provided in the lid and box, and having the ends sealed in the sinkage provided, and as described.

In testimony whereof, I have signed my name to this specification in the presence of two subscribing witnesses.

ROBERT HENDERSON DUNCAN.
